UNITED STATES PATENT OFFICE.

CARL G. NEHLS, OF FLINT, MICHIGAN.

COMBINATION SALT AND PEPPER SHAKER.

Application filed March 20, 1924. Serial No. 700,631.

To all whom it may concern:

Be it known that I, CARL G. NEHLS, a citizen of the United States, residing at Flint, in the county of Genesee and State of

Michigan, have invented certain new and useful Improvements in Combination Salt and Pepper Shakers, of which the following is a specification, reference being had to the accompanying drawings.

10 This invention relates to improvements in salt and pepper shakers or in any combined condiment holder and has for an important object thereof the provision of a neat, readily constructed container having 15 means for selectively delivering one of a plurality of condiments.

An important object of the invention is to provide a device of this character in which the parts may be readily removed for cleansing, all working parts being secured together in a single unit so that they may not become separated and lost.

20 A further object of the invention is to provide a simple device of this character having a single control plate controlling the delivery of a plurality of condiments and means for shifting this control plate to varied selected positions which act to always 25 return the control plate to a position where it closes all outlets and seals the container.

These and other objects I attain by the construction shown in the accompanying drawings wherein for the purpose of illustration is shown a preferred embodiment of 30 my invention and wherein:—

Figure 1 is a perspective view of a combination salt and pepper shaker constructed in accordance with my invention;

Figure 2 is a vertical sectional view thereof;

Figure 3 is a plan view thereof, the control plate being removed;

Figure 4 is a section on the line 4—4 of Figure 2;

Figure 4^a is a section on the line 4^a—4^a of Figure 2;

Figure 5 is an enlarged vertical section through the container and the operating mechanism;

50 Figure 6 is a perspective view of the operating mechanism detached, the cover plate of the operating mechanism being removed;

Figure 7 is an enlarged detail sectional view showing the connections of the push buttons with the shafts;

Figure 8 is a perspective of the push button detached;

Figure 9 is a perspective view showing one of the bearings;

Figures 10, 11 and 12 are diagrammatic views illustrating the operation of the forked levers in coacting with the control plate pin.

Referring now more particularly to the drawings, the numeral 10 indicates a container, the upper end of which is open and provided with a threaded neck 11. Internally the container is provided with a transversely extending division wall 13 dividing the same into two separate compartments, 60 each adapted for the reception of condiment. Aligned with the partition wall 13 the container is provided with a groove 14 formed in its outer wall and having in its base a reduced extension 15 co-extensive with 65 the groove 14 and combining therewith to provide shoulders 16, the purpose of which will presently appear. This reduced extension 15 of the groove 14 continues upwardly through the neck and is provided 70 with an offset forming a horizontally disposed shoulder 17.

Seated upon the upper end of the neck 11 is a disk 18 provided with a series of openings 19 aligning with the compartments at 75 opposite sides of the partition wall 13. Secured to the under surface of this plate is a lug 20 extending into the offset portion of the groove 15 and having secured thereto at the lower end thereof the angular extension 21 of a plate 22 extending downwardly into the groove 15. The lower end of this plate 22 is provided with a second angular extension 23 opposing the angular extension 21 and combining therewith to 80 provide bearings for a pair of shafts 24 and 25 which are of slightly greater length than the plate 20 between the angular extensions thereof and have the excess length thereof 85 arranged above the upper surface of the angular extension surface 21 and between this angular extension and the lower surface of the cover plate 18. To the upper end of the shafts 24 and 25 are secured forks 26 operating in slightly different horizontal 90 planes so that they do not interfere with one another.

At vertically spaced points, the shafts 24 and 25 have secured thereto lever arms 27. Each lever arm 27 aligns with a bearing 100

element 28 formed on the plate 20 through which is extended a reciprocable element 29. The end of the reciprocable element is provided with a vertically extending pin 30 engaging in a slot 31 formed in the lever 27 so that reciprocating motion of the member 29 is transformed to a rocking motion of the shafts 24 and 25 depending upon which of the reciprocating elements is actuated. The outer end of each reciprocating element is provided with a push button head 32 including a flange 33 directed toward the adjacent surface of the plate 20 and within this flange a spring 34 abuts the head in surrounding relation to the reciprocating element and since the opposite ends of these springs engage the plate 20 tends to force this head outwardly. It will be seen that by pushing the selected head 32 the associated shaft 24 or 25 is rocked, the reciprocating elements 29 being disposed intermediate the shafts. The arms connecting these elements to the shafts extend in opposite directions and accordingly opposite rocking motions of the two shafts are provided with the further result that the forks 26 are swung in opposite directions.

Mounted upon the upper surface of the cover plate 18 and pivoted to this plate at the axis thereof, is a control plate 35 having formed therein two sets of openings 36 so arranged that in one position of the plate neither set of openings is aligned with the openings of the cover plate 18. When, however, the plate 35 is shifted to either side of this position, one set of openings will align with the openings of the plate 18 disposed above one of the compartments of the container while the other set of openings remains closed. This plate has projecting downwardly from its under surface a pin 37 extending through a slot 38 formed in the cover plate and projecting into the opening defined by the combination of the forks 26. The forks 26 are so constructed that in their plane of swing either of the forks carries with it the pin 37 thereby shifting the plate 35 to one of the open positions, the remaining fork being undisturbed by the movement of the pin and remaining in proper position to receive the pin when the plate returns to neutral position. In other words, the slot of each fork, when the fork is in normal or inoperative position, is disposed in the plane of movement of the pin to receive this pin. In order that the mechanism hereinbefore described may be enclosed or hidden from view in the completed structure, there is provided a cover plate or mounting bar 39 having properly spaced openings formed therein for the reception of the operating buttons 32 and having upon that surface thereof adapted to be disposed against the plate 20, a recess 40 receiving an aligning pin 41. This pin is located adjacent one end of the

plate 39 preferably the upper end thereof and adjacent the opposite end a securing element 42 is directed through the plate 20 and engaged with the plate 39. The lower end of the slot 15 is provided with a rib 43 engaging in a notch 44 formed in the lower end of the plate 39 maintaining this end of the plate 39 in position in the slot 15 as long as vertical movement of the plate 39 is prevented. The plate 39 is a greater width than the plate 20 which extends into the slot 15 and this plate 39 rests upon the shoulder 16 hereinbefore described. In order to prevent vertical movement of the mechanism and to seal the operating mechanism in position upon the container, the plate 35 is made of less diameter than the cover plate 13 so that the edge of this plate is exposed. A screw cap is provided having a flange 45 engaging this edge to force the plate downwardly into engagement with the upper surface of the container neck. This cap further engages with its lower edge against a reduced tapered extension 46 formed on the upper end of the plate 39 to wedge this end firmly into position against the shoulder 16. It will be obvious that all that is necessary to remove the entire operating mechanism is to remove the cap 45, this releasing all of the mechanism for upward movement and after the mechanism has been moved vertically sufficiently to disengage the rib 43 from the socket 44, this mechanism can be shifted to one side and removed from the container so that it may be boiled or otherwise sterilized without disturbing the contents of the container. By pressing on either button selected condiment can be obtained and since alignment of the apertures is obtained by oscillation of the control plate about its pivot, this oscillation will tend to release any cloggy matter engaged in the openings, particularly as the openings of the cover plate 18 are made larger at their lower ends as explained.

Many changes being possible in the structure of the device as hereinbefore set forth, I do not limit myself to such specific structure except as hereinafter claimed.

What I claim is:—

1. In combination, a condiment container formed to provide two compartments, a cover plate sealing the container and having openings aligned with each compartment, a control plate mounted for oscillation upon the upper surface of the cover plate and having sets of openings selectively alignable with the openings of the cover plate when the control plate is shifted to opposite sides of a central neutral position, a pair of levers engaging the control plate and each operable to shift the control plate to one side of said neutral position and push buttons controlling the operation of the levers, said levers being disposed at the opposite side of

- the cover plate from the control plate and each having a slot, said control plate having a pin extending through a slot in said cover plate for engagement in the slots of said levers and means normally maintaining said levers in a position with the slots thereof opening upon the path of movement of the pin of the control plate whereby the slot of each lever receives the pin when returned to neutral position by the other lever.
2. In combination, a condiment container formed to provide two compartments, a cover plate sealing the container and having openings aligned with each compartment, a control plate mounted for oscillation upon the upper surface of the cover plate and having sets of openings selectively alignable with the openings of the cover plate when the control plate is shifted to opposite sides of a central neutral position, a pair of levers engaging the control plate and each operable to shift the control plate to one side of said neutral position and push buttons controlling the operation of the levers, a plate secured to and supported by said cover plate supporting said push buttons and levers, the outer wall of the container having a groove into which said plate extends, and a cap engaged with the container securing the cover plate in position thereon and maintaining said supporting plate in position within the groove, a cover plate secured to the supporting plate and through which the heads of the push buttons extend, said cap engaging the upper end of said supporting plate to urge the supporting plate downwardly, the lower end of the supporting plate having a groove receiving a rib formed upon the lower end of the slot of the container to maintain the lower end of said cover plate in position.
3. In combination, a condiment container formed to provide two compartments, a cover plate sealing the container and having openings aligned with each compartment, a control plate mounted for oscillation upon the upper surface of the cover plate and having sets of openings selectively alignable with the openings of the cover plate when the control plate is shifted to opposite sides of a central neutral position, a pair of levers mounted upon spaced pivots and having their ends forked, a pin carried by the control plate, means normally maintaining the levers in a position in which both receive the pin of the cover plate and the fork thereof, the openings of the forks of said levers being disposed in the plane of movement of the pin whereby said pin when returned to the neutral position by a lever through which it has been operated is entered in the opening of the fork of the other lever.
4. In combination, a condiment container formed to provide two compartments, a cover plate sealing the container and having openings aligned with each compartment, a control plate mounted for oscillation upon the upper surface of the cover plate and having sets of openings selectively alignable with the openings of the cover plate when the control plate is shifted to opposite sides of a central neutral position, a pair of levers engaging the control plate and each operable to shift the control plate to one side of said neutral position and push buttons controlling the operation of the levers, a plate secured to and supported by said cover plate supporting said push buttons and levers, the outer wall of the container having a groove into which said plate extends, and a cap engaged with the container securing the cover plate in position thereon and maintaining said supporting plate in position within the groove, a cover plate secured to the supporting plate and through which the heads of the push buttons extend, said cap engaging the upper end of said supporting plate to urge the supporting plate downwardly, the lower end of the supporting plate having a groove receiving a rib formed upon the lower end of the slot of the container to maintain the lower end of said cover plate in position.

In testimony whereof I hereunto affix my signature.

CARL G. NEHLS.
